UNITED STATES PATENT OFFICE.

GUY B. WAITE, OF NEW YORK, N. Y.

RIB FOR WALLS AND THE LIKE.

932,197.

Specification of Letters Patent. Patented Aug. 24, 1908.

Application filed April 6, 1906. Serial No. 252,233.

To all whom it may concern:

Be it known that I, GUY B. WAITE, a citizen of the United States, residing at New York, in the county and State of New York, 5 have invented certain new and useful Improvements in Ribs for Walls and the Like, of which the following is a specification.

My invention relates to metal ribs or strips which are used in building structures, 10 and which are adapted to constitute mechanical fastening devices for uniting the meeting ends of building blocks and the like, in lieu of mortar or cement; and it consists in the novel form and structure of such a 15 strip substantially as hereinafter described and pointed out in the claims.

In the accompanying drawing—Figures 1 and 2 are plan and end views, respectively, 20 of a sheet metal blank from which my improved rib in its preferred form may be made; Figs. 3 and 5 are side and edge views of the rib made from the blank shown in Fig. 1; Figs. 4 and 6 are cross sectional views on the lines 4—4 and 6—6 of Figs. 3 and 5, respectively; Figs. 7 and 9 are views of the opposite sides of a modified form of the rib shown in Figs. 3 to 6; Figs. 8 and 10 are cross sectional views on the lines 8—8 and 10—10 of Figs. 7 and 9, respectively; Figs. 35 11 and 12 are, respectively, edge and cross sectional views of the rib shown in Figs. 7 to 10; Fig. 13 is a perspective view of a wall embodying in its construction the forms of ribs illustrated in the preceding figures; Fig. 14 shows a horizontal section through the wall of Fig. 13.

My preferred form of rib is illustrated in Figs. 1 to 6, inclusive, the finished form of the rib being designated as an entirety by A. 40 To make this rib I take a plain flat strip, preferably of sheet metal, designated a in Figs. 1 and 2, and bend over the longitudinal marginal portions thereof on the lines 1, 1, thus forming oppositely extending lateral 45 flanges 2, 2, (Figs. 3 and 4). From the intermediate body portion of the strip I cut or stamp two series of tongues 3, 3, one on each edge in the planes of the flanges 2, 2, respectively; thereby forming a double channel 50 shaped member provided in effect with clips on both sides thereof adapted to engage the outer surfaces of building blocks, boards, or other elements interposed between adjacent ribs.

Figs. 7 to 12 inclusive illustrate a slightly different manner of bending the blank a to

form a rib which I have designated as an entirety A'. In this form, the marginal portions 5, 5, are both bent on the same side of the web, and the tongues 6, 6, are both bent 60 in the opposite direction.

Turning now to an explanation of the uses of the ribs previously described, and their manner of incorporation in building structures such as partition and other walls, D, 65 Figs. 13 and 14, may designate as an entirety, a partition wall, wherein the principal building material comprises rectangular concrete or other blocks d laid up in vertical and horizontal edgewise juxtaposition. Between the 70 adjacent ends of these blocks, and for the purpose of retaining the latter in proper position and uniting them into a strong rigid structure, are the ribs previously described; the two ribs nearest the left of the 75 figure being of the form A, and the two ribs nearest the right of the figure being of the form A'. Fig. 14 shows plainly the manner in which the laterally projecting margins and tongues of the ribs constitute clips 80 securely uniting the abutting ends of adjacent blocks. Fig. 14 also shows how my improved ribs lend themselves to convenience in the operation of erecting the wall; since, by bending the tongues 3 or 6 as the 85 case may be, out away from the plane of the wall, the building block can be readily inserted into place laterally, after which the tongues can be bent back into holding 90 engagement with the block.

From the foregoing it will be seen that my invention provides a useful and convenient building element capable of being simply and cheaply bent and struck up from a sheet metal blank with capacity for engaging and securing in alignment blocks, planks or other like building elements between proximate ends or edges of which such element is interposed.

I claim:

1. As a new article of manufacture, a rib for walls and the like comprising a flanged strip adapted to be interposed between the proximate edges of adjacent building blocks, said strip having cut and bent out from the central portion thereof between the flanges projections adapted to engage and hold the faces of the blocks, substantially as described.

2. As a new article of manufacture, a rib for the purposes described formed from a 110 flat strip of sheet metal having a longitudinal edge portion thereof bent to form a lateral

projection on one side, and having a series of tongues cut and bent from the central portion of the strip and projecting on the opposite side in the plane of said bent edge portion, substantially as described.

3. As a new article of manufacture, a rib for the purposes described formed from a flat strip of sheet metal having each of its longitudinal edge portions bent into a plane

at right angles to its central portion, and also having punched from the latter tongues extending in opposite directions to said bent edge portions and in the planes of the latter, substantially as described.

GUY B. WAITE.
